UNITED STATES PATENT OFFICE.

JULIUS B. WANTZ, OF CHICAGO, ILLINOIS, ASSIGNOR, BY MESNE ASSIGNMENTS, TO VICTOR ELECTRIC CORPORATION, OF CHICAGO, ILLINOIS, A CORPORATION OF NEW YORK.

X-RAY TABLE.

1,239,146.

Specification of Letters Patent. Patented Sept. 4, 1917.

Application filed February 16, 1914. Serial No. 818,926.

To all whom it may concern:

Be it known that I, JULIUS B. WANTZ, a citizen of the United States, residing at Chicago, in the county of Cook and State of Illinois, have invented a new and useful X-Ray Table, of which the following is a specification.

My invention relates to X-ray tables for use with X-ray apparatus, and more particularly to combined means for changing plates and supporting a patient during the taking of X-ray pictures; my primary object being to provide improved means for rapidly changing the plates and for supporting the patient in horizontal or inclined position, as desired.

Referring to the accompanying drawings—

Figure 1 is a perspective view of a combined table and plate-changer constructed in accordance with my invention. Fig. 2 is a similar view of the top portion of the table showing the underside thereof. Fig. 3 is an enlarged section taken at the line 3 on Fig. 2 and viewed in the direction of the arrow. Fig. 4 is an enlarged section taken at the line 4 on Fig. 6 and viewed in the direction of the arrow. Fig. 5 is a view in elevation, partly sectional, of a portion of the means 25 for holding the table-top in adjusted position. Fig. 6 is a bottom plan view of the carriage which travels in the table-top, a portion of the table-top proper and certain parts connected therewith also being shown. Fig. 7 is a section taken at the line 7 on Fig. 6 and viewed in the direction of the arrow. Fig. 8 is an enlarged section taken at the line 8 on Fig. 6 and viewed in the direction of the arrow. Fig. 9 is a section 35 taken at the line 9 on Fig. 6 and viewed in the direction of the arrow. Fig. 10 is a plan view of the plate-supporting slide employed. Fig. 11 is an edge view of the slide of Fig. 10. Fig. 12 is a perspective view of 40 another form of plate-holding device which may be used in connection with the table under certain conditions; and Fig. 13 is a section showing, in elevation, a convertible rest and seat employed in connection with 45 the table-top.

The main-frame of my improved structure is represented at 14 and comprises end-frames formed of side bars 15 and upper and lower bars 16 and 17, respectively, two 50 parallel side members 18 connected with the

end-frames and a single lower bar 19 likewise connected with these frames. The top of the table, represented at 20, is formed of channeled side-members 21 connected together by end-pieces 22 and by cross-braces 23 and 24, and plate sections 25 and 26 toward its opposite ends, of material preferably opaque to X-rays, leaving a space between, which is covered over with a sheet 27 of material transparent to X-rays, the structure thus illustrated constituting in effect a tunnel having a window-section 27 through which the exposures are made, as hereinafter more fully referred to. The table-top, or tunnel structure just described, is provided 55 near one end and at opposite sides with U-shaped clips 28 which fit over the forward one of the rods 16, with pins 29 connecting the ends of the loops together to form 60 socket-members at which the table-top is fulcrumed on the rod 16, the opposite end of the table-top being provided with depending lugs 30 having recessed heads 31 adapted to 65 rest upon the bars 18 at opposite sides of the frame when the table-top is in its lowermost position. Located in the channel-irons 70 21, preferably closely adjacent to the upper flanges thereof, are bars 32 which form 75 guides for a carriage slidably mounted in the tunnel, or table-top, and engaging the 80 rods 32 at rollers 33 thereon, the carriage being formed of side members 34 provided 85 with inwardly-opening channels 35, and cross-pieces 36, 37 and 38 connecting these side members together, the carriage being 90 adapted to receive the plate-holding slide, represented at 39, which is preferably formed of two similar sections 40 and 41 hingedly connected together, as indicated at 95 42, and adapted to enter the channels 35, thus telescoping with the carriage, the slide 39 when completely telescoped with the carriage serving to register the forward photographic plate secured thereon, as hereinafter 100 described, with the window-section 27.

The carriage is adapted to be projected to the left in Fig. 1 from the position in which the forward plate on the slide 39 registers with the window-section 27, to a position in which the rear plate on the slide 105 39 registers with this section for thus effecting the changing of the plates. The means for thus operating the slide 39 comprise a spring 43 secured at one end to the cross-piece 23 and at its opposite end to a 110

cross-piece 37 on the carriage, this spring being placed under tension when the operator, by grasping a handle 45 on the carriage, slides the latter to the right in Fig. 1 for causing the forward plate on the slide 39 to register with the window-section 27. In this position the carriage is releasably held by locking means, those shown comprising a socket member 46 which passes 10 through an opening 46^a in one of the rails 47, which are secured at opposite sides of the top and spaced therefrom, and screws at its threaded end 48 into an opening 21^a in the adjacent channel member 21, a plunger 49 slidable in the casing 46 and adapted to normally project, under the action of a coiled spring 50 in the casing 46, into the path of movement of a lug 51 on the side of the carriage. It will thus be understood 20 that when the plunger 49 is withdrawn from engagement with the lug 51, as by pulling on a cord 52 secured to the inner end of the plunger, the spring 43 will rapidly shift the carriage to the left in Fig. 1.

25 It is desirable that each rail 47 contains an opening 46^a and each channel-member 21 contain an opening 21^a to permit the locking means described to be transferred from one side of the table to the other thereof at 30 will, as conditions require.

Coöperating with the carriage are means for limiting its movement to the left in Fig. 1 for positioning, relative to the section 27, the rear plate carried on the slide 39, and cushioning it to prevent jar, these means comprising a cylinder 63 secured to the table-top, a piston 64 slidable in the cylinder 63 and carrying a stem 65 which is connected with said carriage, as indicated 40 at 66, and means for controlling the exhaust of air in the cylinder 63 in the movement of the carriage to the left in Fig. 1. The preferred construction of the last-referred to means comprises a sleeve 67 secured to one end of the cylinder 63, and carrying a boss 68 which opens into the interior of the cylinder 63 through an opening 69. Surrounding this boss is a sleeve 70 which is slidable thereon and closed at one 45 end, excepting preferably for a small opening 71. The boss 68 and sleeve 70 also contain openings 72 and 73 adapted normally to register with each other. The sleeve 70 also contains an elongated slot 74 through 50 which a post 75, secured in the boss 68, extends (Fig. 7); this post coöperating with an adjustable pin 76 screwed into a lug 77 carried by a ring 78 surrounding and rigid with the sleeve 70. A coiled spring 79 sur-

60 rounds the sleeve 70 and is confined between the collar 78 and the sleeve 67, this spring tending to force the sleeve 70 to the left in Fig. 7 and restrained by the engagement of the pin 76 with the post 75. It will be mani- 65 fest that by adjusting the pin 76, the size

of the outlets through the opening 74 and the openings 72 and 73 may be varied as desired, and thus the speed at which the carriage is moved under the action of the spring 43 may be varied, as desired. In the 70 construction illustrated, an auxiliary opening, represented at 80, and provided with an adjustable valve 80^a, is provided for the cylinder 63, and an inlet check-valve 81 is provided in the closed end of the cylinder 63. 75 The carriage is brought to a stop by the seating of a coiled spring 65^a against the inner end of the cylinder 63.

As hereinbefore stated, the table-top is adapted to be tilted upwardly at its rear 80 end by swinging it on the forward bar 16 as a fulcrum, and as means for releasably securing the table-top in the different inclined positions to which it may be adjusted, I provide the following described means: 85 Pivotally connected at their upper ends, as indicated at 82, to the cross brace 23 are bars 83 pivotally connected at their lower ends, as indicated at 84, to a sleeve-section 85 slidable lengthwise on the bar 19. The 90 sleeve-section 85 has journaled therein between its ends, as indicated at 86, a foot lever 87 provided at one end with a depending pin 88 which slides in an opening 89 in the upper side of the sleeve 85, and is adapt- 95 ed to enter any one of the openings 90 pro- 100 vided in the upper side of the bar 19. It will be readily understood that when the table-top is to be moved to tilted position, the operator will press down on the lever 87 to lift the pin 88 out of the opening 90 which thus permits the top to be swung upwardly, and when the desired position of adjustment has been effected, projecting the pin 88 into the appropriate opening 90. In 105 the particular construction illustrated, a spring 91 is located between the lever 87 and sleeve 85 and tends to yieldingly force the pin 88 downwardly, so that it will automatically enter any one of the openings 90 110 into registration with which it is moved.

It is preferred that the cushioning means for the carriage be so adjusted that when the carriage is horizontal it will come to rest upon being moved to the left in Fig. 1 115 by the spring 43, as quickly as possible and still cushion it. It will thus be manifest that the adjustment of the outlets hereinbefore described, of the cushioning means, for performing their function when the carriage is moving in a horizontal plane, will not be correct when the table-top, with the carriage, is tilted, as hereinbefore explained, as the nearer these parts approach a vertical position, the greater will be the force of 120 gravity acting on the carriage. I have, therefore, devised, as a part of my improved table, means which shall operate automatically to vary the outlets for the cushioning means to compensate for the progressively 125 130

increasing force of gravity as the table-top is adjusted to positions wherein it more closely approaches the vertical plane, a description of these means being as follows:

- 5 Secured to the forward bar 16 on which the table-top is fulcrumed at the members 28, is an arc-shaped plate 92 which extends above said rod and is preferably secured thereto through the medium of a split collar-section 93. The plate 92 is so positioned as to coact with the outer end of the sleeve-section 70 which is projected outwardly and held in position against this plate by the spring 79, one end of this plate being deflected as represented at 92^a, at which end the sleeve-section 70 bears when the table-top is horizontal, thus causing the spring 79 to project the sleeve-section 70 to the position illustrated in Fig. 7, wherein the air-discharge openings are caused to assume maximum proportions and suitable for permitting the air to escape from the cylinder 63 at the right speed in the movement of the carriage to the left in Fig. 1. As the table-top is swung upwardly on its fulcrum, the plate 92 being stationary, the sleeve-section 70 is forced to the right in Fig. 7 to a degree depending upon the position to which the table-top is swung, thereby throttling 30 the air outlet passage for the cylinder 63, the degree of throttling depending upon the position to which the table-top is moved.
- The plate-carrying slide may be of any desirable construction, but it is preferred that it be provided with means for holding the plates when merely inclosed in envelopes or when inclosed in regular plate-holders which usually are comparatively thick. To this end I preferably provide the plate-sections 40 and 41 with longitudinally extending centralized slots 93 through which set-screws 94, provided in bars 95, project, these set-screws screwing into nuts 96 located on the underside of the sections 40 and 41, the bars 95 being provided on the upper side of the sections 40 and 41 and being provided at opposite edges with clips 97 and 97^a, the clips 97 being preferably of springy material for holding a plate inclosed in an envelop, represented at X, in proper position on the slide 39, as shown in the left-hand end in Figs. 10 and 11, and the clips 97^a, which are preferably provided with rubber sheathing 98, so proportioned that they will 50 firmly hold a plate-holder, represented at Y, in place on the slide 39, as represented at the right-hand ends of Figs. 10 and 11, it being understood that the bars 95 may be adjusted along the slots 93, relative to each other, to 55 accommodate plates or plate-holders of different sizes.

In stereoscopic work it is necessary that the second plate to be exposed be moved into a certain predetermined position relative to 60 the position occupied by the first plate when

the latter was exposed. It is, therefore, preferred that some guide means be provided on the sections 40 and 41 in order that the operator may quickly and accurately position the plates as desired. In Fig. 10, I have illustrated a desirable manner of so guiding the operator, the means there shown being represented by the guide lines 99. The lines 99 are provided for different sizes of plates and enables the plate to be centered quickly and accurately regardless of the positioning of the plate lengthwise of the slide 39 or crosswise thereof, as will be manifest from an examination of the drawing.

Another feature of my invention consists in the provision of a rest 100 pivotally connected, as indicated at 101, to uprights 102 vertically adjustable in heads 103 slidably confined on the rails 47 (Fig. 13), the uprights 102 being adapted to be held in vertically adjusted position through the medium of set-screws 104 carried by the heads and bearing against these uprights. The upper ends of the uprights 102 contain arc-shaped slots 105 in which set-screws 106, connected with the head-rest 100 at opposite ends thereof, extend, and by means of which the rest may be secured in adjusted position. The provision of the heads 103, which are 95 slidable on the rail 47, permit the rest 100 to be positioned at any point desired along the table-top. The rest 100 may be used as a rest for either the head or feet of the patient, and, if desired, may be used as a seat 100 for the patient when the table-top is tilted to approximately upright position.

As an adjunct to my improved structure, which may or may not be used therewith as desired, I provide a holder for a plate which 105 is useful under certain conditions when it is desired that the plate extend either above or below the body of the patient. This plate-holder is formed of a housing 107 in which a slide 108 for a plate, is mounted, 110 the side of the housing 107 shown uppermost in Fig. 12 and which is lowermost in Fig. 1 being preferably formed of material transparent to X-light. The housing 107 is provided with a cross-piece 109 provided 115 with a lug 110 to which a recessed head 111 is adjustably connected as through the medium of a set-screw 112. Fitting into the socket 113 in the head 111 is a rod 114, the inner end of which contains an annular recess 115 into which a pin 116 in the socket 113 extends, to provide a swivel-connection between the head 111 and the rod 114. The other end of the rod 114 passes through a sleeve-member 117 containing a set-screw 118 120 adapted to secure the rod 114 in any position of adjustment in said sleeve, this sleeve being provided with a tubular downwardly-extending portion 119, the socket 120 of which, receives an upright rod 121 vertically 130

adjustable in a head 122 and held therein in adjusted position by means of a set-screw 123, the head 122 being slidably confined on the guideway 47 and adapted to be held in 5 adjusted position thereon through the medium of set-screws 124.

It will be understood from the foregoing that the housing 107 may be adjusted in any desired position relative to the body of the 10 patient either as regards elevation or inclination, the various adjusting devices described permitting a wide range of movement of the housing 107.

While I have illustrated and described a 15 particular embodiment of my invention, I do not wish to be understood as intending to limit it thereto, as the same may be variously modified and altered without departing from the spirit of my invention, it being my desire to claim my invention as 20 broadly and completely as the prior state of the art will permit.

What I claim as new and desire to secure by Letters Patent is—

- 25 1. In apparatus of the character set forth, the combination of a base, a table-top fulcrumed thereon, means for holding said table-top in inclined position on said base, a plate-carrier movably mounted on said 30 table-top, means for shifting said carrier, cushioning means for said carrier, and means operating automatically to adjust the action of said cushioning means upon the act of moving said table-top to inclined position.
- 35 2. In apparatus of the character set forth, the combination of a base, a table-top fulcrumed thereon, means for holding said table-top in inclined position on said base, a plate-carrier movably mounted on said table-top, means for shifting said carrier, dash- 40 pot cushioning means for said carrier, and means operating automatically to vary the air-outlet of said dash-pot upon the act of moving said table-top to inclined position.
- 45 3. In apparatus of the character set forth, the combination of a base, a table-top fulcrumed thereon, means for holding said table-top in inclined position on said base, a plate-carrier movably mounted on said 50 table-top, means for shifting said carrier, dash-pot cushioning means for said carrier including an air-outlet-varying device, and means on said base coöperating with said device and operating automatically to vary 55 the air-outlet of said dash-pot upon the act of moving said table-top to inclined position.

- 60 4. In apparatus of the character set forth, the combination of a base, a table-top fulcrumed thereon, means for holding said table-top in inclined position on said base, a plate-carrier movably mounted on said table-top, means for shifting said carrier, dash-pot cushioning means for said carrier, 65 including relatively movable parts for vary-

ing the air-outlet of the dash-pot, and a cam on said base coöperating with said air-outlet-varying means, for the purpose set forth.

5. In apparatus of the character set forth, 70 the combination of a base, a movably-supported plate-carrier on said base, means for shifting said carrier on said base, and a trigger device for releasably holding said carrier in a predetermined position and in 75 opposition to said means, transferable from one side of said base to the other side thereof.

6. In apparatus of the character set forth, 80 the combination of a base, a movably-supported plate-carrier on said base, stops provided at opposite sides of said carrier, and a trigger device adapted to releasably engage one of said stops for holding said carrier in a predetermined position and in opposition to said means, said trigger device being transferable from one side of said base to the other side thereof to coöperate 85 with either of said stops.

7. In apparatus of the character set forth, 90 the combination of a base, a movably-supported plate-carrier on said base provided with stops at its opposite sides, means for shifting said carrier on said base, and a 95 trigger device for releasably engaging said stops when said carrier is in a predetermined position and in opposition to said means, said trigger device including a member forming a bearing adapted to be inserted into either one of the openings in said base adjacent to said stops, whereby the trigger device may be caused to coöperate with either one of said stops, for the 100 purpose set forth.

8. In apparatus of the character set forth, 105 the combination of a base, a movably-supported plate-carrier on said base provided with projections at its opposite sides, means for shifting said carrier on said base, and a trigger device for coöoperating with said stops to releasably hold said carrier in a predetermined position and in opposition to said means, said trigger device being formed of a casing having a threaded end, 110 a spring-controlled plunger projecting through the threaded end of the casing and at which the trigger device coöperates with said stops, said base containing threaded openings at its opposite sides adjacent said stops into either one of which said casing 115 may be screwed, for the purpose set forth.

9. In apparatus of the character set forth, 120 the combination of a base, a table-top fulcrumed thereon, means for holding said table-top in inclined position on said base, a plate-carrier movably mounted on said table-top, means for shifting said carrier, dash-pot cushioning means for said carrier, 125 means operating automatically to vary the air-outlet of said dash-pot upon the act of moving said table-top to inclined position.

- air-outlet of said dash-pot upon the act of moving said table-top to inclined position, and an auxiliary air-outlet for said dash-pot provided with a valve.
- 5 10. A plate-holding device comprising a plate adapted to have a plate applied thereto and reversible clips on said plate provided with plate-engaging members at their opposite edges, the said members at one edge 10 of each clip device being offset to a greater degree than those at the opposite edge of each clip-device.
11. A plate-holding device comprising a plate adapted to have a plate applied thereto and clips pivotally supported on said plate and provided with plate-engaging members at their opposite edges, the said members at one edge of each clip device being offset to a greater degree than those at the opposite edge of each clip-device, and means for securing said clips in their positions of pivotal adjustment.
12. In apparatus of the character set forth, the combination of a base, a table-top thereon, a carriage movably supported on said table-top, and a slide, adapted to have plates applied thereto, telescoping with said carriage.
13. In apparatus of the character set forth, the combination of a base, a table-top thereon, a carriage movably supported on said table-top, means for shifting said carriage, and a slide, adapted to have plates applied thereto, telescoping with said carriage.
- 35 14. In apparatus of the character set forth, the combination of a base, a table-top thereon, a carriage movably supported on said table-top and a slide adapted to have plates applied thereto carried by said carriage.
- 40 15. In apparatus of the character set forth, the combination of a base, a table-top thereon, a carriage movably supported on said table-top at opposite sides of the latter, and a plate-holding slide carried by said carriage.
- 45 16. In apparatus of the character set forth, the combination of a base, a table-top thereon, a carriage movably supported on said table-top, and a slide formed of hinged 50 connected sections and adapted to have plates applied thereto carried by said carriage.
17. In apparatus of the character set forth, the combination of a base, a table-top thereon, a carriage in the form of a frame telescoping with said table-top, and guided thereon at its edges, and a plate-holding slide telescoping with said carriage.
- 60 18. In apparatus of the character set forth, the combination of a base, a table-top thereon, a carriage movably supported on said table-top, a plate-supporting slide carried by said carriage, and adjustable clip-devices carried by said slide for securing plates thereto.
19. In apparatus of the character set forth, the combination of a base, a table-top, a carriage movable thereon, a slide carried by said carriage and adapted to have a plate applied to a side thereof, and means for holding the plate in position on said slide.
20. In apparatus of the character set forth, the combination with a table, of a reversible member mounted on said table to extend above the same, and means on said member for holding a plate in position beneath said member.
21. In apparatus of the character set forth, the combination of a table having a longitudinally-extending guide at one side, a block engaging said guide and adjustable lengthwise thereof, an upright vertically adjustable on said block, a head pivotally mounted on said upright, a rod longitudinally adjustable on said head, and a plate-holding member pivotally supported on said rod.
22. In apparatus of the character set forth, the combination of a base, a plate-carrier movably supported thereon, a series of rectangular guide-marks on the portion of said carrier superposed by the plate, and having a common center, and a second series of rectangular guide-marks having a common center on said portion of said carrier, 95 said second series of guide-marks being disposed at right angles to said first-named series of guide-marks.
23. In apparatus of the character set forth, the combination with a table, of a member mounted to extend above the table and adapted to have an X-ray plate applied thereto to a predetermined position thereon, and means on said member coincident with the center of the plate when the latter is 100 positioned on said member, for indicating to the operator the location of the center of the plate.
24. In apparatus of the character set forth, the combination with a table the top 110 of which has a section of material transparent to X rays and carries a mark forming a guide in the positioning of the patient on the table, a carrier for an X-ray plate mounted to be moved beneath said transparent section to move a plate thereon into registration therewith, means for centering plates of different sizes on said carrier relative to a predetermined point thereon, and means whereby the said predetermined point 115 on said carrier may be caused to be moved into registration with the said marking on said transparent section of the table-top.
25. In apparatus of the character set forth, the combination with a table the top 120 of which has a section of material transparent to X rays and carries a mark forming a guide in the positioning of the patient on the table, a carrier for X-ray plates to support the plates at different points along 130

- the carrier, said carrier being mounted to be moved beneath said transparent section, means for centering plates of different sizes on said carrier relative to predetermined points thereon, and means whereby either of said predetermined points on the carrier may be caused to be moved into registration with the said marking on said transparent section.
- 10 26. In apparatus of the character set forth, the combination with a table having a top, a section of which is of a material transparent to X rays, of a carrier mounted to be moved beneath and in a plane substantially parallel with the plane of said transparent section and adapted to support a plurality of X ray plates applied thereto at different points along its length, means on said carrier for centering X ray plates of different sizes relative to a plurality of predetermined points on said carrier, means co-operating with said carrier and operating in the shifting of said carrier to insure registration of said predetermined points on the carrier, in the successive operations of the latter, with a given point on said transparent section, and means on said transparent section for indicating to the operator the point thereon with which the centers of the X ray plates register in the successive operations of the carrier.
- 25 27. In apparatus of the character set forth, the combination with a table having a top, of a member supported on the table and adjustable about a substantially vertical axis, a reversible member mounted on said first-named member to extend above the table-top, and means on said last named member for holding a plate in position beneath the latter.
- 30 28. In apparatus of the character set forth, the combination with a table having
- 35 a top, of a member supported on the table and adjustable about a substantially vertical axis, a second member supported on said first-named member and adjustable about an axis at an angle to the axis of said first-named member, a third reversible member mounted on said second member to extend above the table-top, and means on said third member for holding a plate in position beneath the latter.
- 40 29. In apparatus of the character set forth, the combination with a table having a top, of a member supported on the table and adjustable about a substantially vertical axis, a second member supported on said first-named member and adjustable about an axis at an angle to the axis of said first-named member and adjustable lengthwise of said first-named member, a reversible member mounted on said third member to extend above the table-top, and means on said reversible member for holding a plate in position beneath the latter.
- 45 30. In apparatus of the character set forth, the combination with a table having a top, of a member supported on the table and adjustable about a substantially vertical axis, a second member supported on said first-named member and adjustable about an axis at an angle to the axis of said first-named member and adjustable lengthwise of said first-named member, and a third member reversible on said second member about an axis extending at an angle to the axes of both said first and second-named members, said third member extending above the top of the table.
